UNITED STATES PATENT OFFICE.

JOHN L. WILLIAMS, OF NEW HAVEN, CONNECTICUT.

ACID-HOLDER FOR FIRE-EXTINGUISHERS.

SPECIFICATION forming part of Letters Patent No. 719,403, dated January 27, 1903.

Application filed April 28, 1902. Serial No. 105,120. (No model.)

To all whom it may concern:

Be it known that I, JOHN L. WILLIAMS, a citizen of the United States, residing at New Haven, in the county of New Haven and State 5 of Connecticut, have invented certain new and useful Improvements in Acid-Holders for Fire-Extinguishers; and I do hereby declare the following to be a full, clear, and exact description of the invention, such as will enable others skilled in the art to which it 10 pertains to make and use the same.

This invention has relation to means for holding a reagent for chemical fire-extinguishers, whereby the gas-producing medium may 15 be instantly and positively discharged, so as to produce the pressure within the tank or body of the extinguisher necessary to expel the extinguishing fluid therefrom.

The purpose of the invention is the provision 20 of a supporting means for the bottle or other package containing the reagent which may be applied to any chemical fire-extinguisher and which will admit of the bottle or package being refilled or substituted by a 25 new one when required.

For a full description of the invention and the merits thereof and also to acquire a knowledge 30 of the details of construction of the means for effecting the result reference is to be had to the following description and drawings hereto attached.

While the essential and characteristic features 35 of the invention are susceptible of modification, still the preferred embodiment of the invention is illustrated in the accompanying drawings, in which—

Figure 1 is a perspective view of the invention. Fig. 2 is a detail section showing the relation of the parts when the bottle or 40 vessel containing the reagent has been tilted so as to discharge its contents.

Corresponding and like parts are referred to in the following description and indicated in both views of the drawings by the same reference characters.

The numeral 1 represents a plug to be fitted into an opening in the upper portion of a tank 2 or other receptacle containing the extinguishing fluid. This plug is provided with 45 opposite extensions 3 for the fingers of the hand to obtain a purchase upon when tightening or loosening the plug. A stem 4 passes

centrally through a stuffing-box 5, applied to the plug 1, and is provided at its inner end with a stopper or closure 6 and at its outer 55 end with a handle 7. Hangers 8 are pendent from the plug 1, and the bottle, package, or vessel 9, containing the chemical reagent, is pivoted between the lower ends of the hangers 8 and is adapted to be closed by the stopper 6 at the lower end of the stem 4. A flexible connection 10 connects the lower portion of the stem 4 with the upper part of the bottle or vessel 9 and is of such relative length as to admit of an upward movement of the 60 stem to uncork the bottle 9, after which a continued upward movement of the stem effects a tilting of the bottle through the connection 10, as indicated most clearly in Fig. 2.

The plug 1 is of a size to admit of the bottle 9 and adjunctive parts pendent from the lower side of the plug to readily pass through the opening of the tank, body, or receptacle 2, adapted to be closed by said plug when the latter is in place. It will thus be seen that 75 access can be readily had at any time to the part 9 either for inspection, for replenishing, or for any desired purpose. When the plug 1 is removed, the bottle 9 can be easily filled and corked, the parts being placed in position with despatch and a minimum amount of trouble. When it is required to use the extinguisher, it is only necessary to grasp the handle 7 and draw upward upon the stem 4. The first movement uncorks the bottle, and a 80 continued upward movement of the stem tilts the bottle and discharges its contents into the tank or receptacle containing the extinguishing fluid and mixing therewith generates gas and creates a pressure which expels the extinguishing fluid in a stream from 85 the hose-pipe in the well-known manner.

The stopper 6 is of metal, lead being preferred, and is protected by a layer or coating of rubber, which enables a close fit with the 90 neck of the bottle being obtained and at the same time prevents the acid or other agent acting upon the body of the stopper.

The plug 1 may be of any size and in some instances may consist of a cap or cover of the 100 tank or receptacle containing the extinguishing fluid. The size of the plug is immaterial so long as it closes the opening through which the bottle or vessel is inserted into the reser-

voir, tank, or other receptacle forming the body of the extinguisher.

Having thus described the invention, what is claimed as new is—

- 5 In combination, a plug for closing an opening in the body of a chemical fire-extinguisher, hangers pendent from the plug, a bottle or package containing a chemical reagent suspended from said hangers, a stem mounted 10 in the plug for reciprocal movement and adapted to operate between the hangers, a stopper at the lower end of the stem, a flexible connection between the stem and the body

portion of the bottle, said connection admitting of a limited upward movement of the 15 stem to unseat the stopper and upon further upward movement to effect a tilting of the bottle to discharge the contents thereof, substantially as and for the purpose set forth.

In testimony whereof I affix my signature 20 in presence of two witnesses.

JOHN L. WILLIAMS. [L. S.]
